UNITED STATES PATENT OFFICE.

JOHN RICE, OF SALINEVILLE, OHIO.

MOTOR-DRIVEN LUBRICANT-FEEDER.

1,185,713.

Specification of Letters Patent.

Patented June 6, 1916.

Application filed April 15, 1914. Serial No. 832,059.

To all whom it may concern:

Be it known that I, JOHN RICE, a citizen of the United States, residing at Salineville, in the county of Columbiana and State of Ohio, have invented a new and useful Motor-Driven Lubricant-Feeder, of which the following is a specification, reference being had to the accompanying drawings, and to the letters and figures of reference marked 10 thereon.

This invention relates to apparatus for forcing lubricating oil to various parts of machinery or into valve chests of steam cylinders, or wherever the oil may be required, 15 the invention having reference more particularly to a motor-driven lubricant-feeder adapted to be operated independently of the engine or machine to which it may be feeding the lubricant.

20 An object of the invention is to provide a simple and reliable lubricant-feeder, more particularly of the multiple feed type, and which shall be so constructed as to be complete and self-contained and not be dependent upon moving machinery from which to derive motion, to the end that the lubricant-feeder may be conveniently placed in the cab of a locomotive or portable engine where the lubricant will not be exposed to low 25 temperatures and become thick, such position permitting the engine men to conveniently take care of the feeder and readily see at all times that it is properly operating when required.

30 Another object of the invention is to provide a motor-driven lubricant-feeder that shall be adapted to be operated either by means of steam or by compressed air in order that the feeder may be conveniently 35 located in a warm position and be capable of furnishing the lubricant before the engine or machinery is put in motion, thus eliminating the disadvantages of lubricant-feeders that derive their motion from moving 40 parts of machinery.

A still further object of the invention is to provide a lubricant-feeder of such construction as to be readily adaptable for feeding oil to any desired number of points 45 from one reservoir so that one feeder only requires attention in the regulation of the feeding capacity, and in filling the reservoir and starting or stopping the feeder, a requirement in many power plants.

With the above-mentioned and other objects in view, the invention consists in a lubricant-feeder comprising a reservoir containing one or more pump or pumps for feeding oil from the reservoir, and actuating mechanism for the pump or pumps provided with a motor that is mounted on the reservoir and preferably adapted to be actuated by means of steam or compressed air, the oil feeder including improvements in various features of the pumping apparatus and also in the operating mechanism therefor; and the invention consists further in the novel parts and combinations and arrangements of parts as hereinafter particularly described and further pointed out in the accompanying claims.

Referring to the drawings, Figure 1 is an elevation of the improved lubricant feeder constructed substantially in accordance with the invention; Fig. 2, a vertical section on the line A A in Fig. 1; Fig. 3, a fragmentary section on an enlarged scale on the line B B in Fig. 2; Fig. 4, a perspective view of one of the parts of the pump-operating mechanism; Fig. 5, a sectional view approximately on the line C C in Fig. 2; Fig. 6, a horizontal section approximately on the line D D in Fig. 1; Fig. 7, a fragmentary section on the line E E in Fig. 6; Fig. 8, a fragmentary section on the line F F in Fig. 7; Fig. 9, a fragmentary section on the line G G in Fig. 6; Fig. 10, a fragmentary section of one of the outlet or delivery pipes and a valve therein, and Fig. 11 is a fragmentary section showing details of one of the conduits of the improved pump.

In the different figures of the drawings corresponding reference characters indicate like parts or features of construction herein referred to.

As illustrative of the construction and mode of operation of the improved lubricant-feeder, a machine is shown which conveniently is adapted for feeding lubricant through three lines of piping from a single reservoir which comprises a bottom 1 on which is a side wall comprising two oppositely arranged straight portions 2 and 3 and two other oppositely arranged portions 4 and 5, one wall portion preferably being provided with a drain plug 6, two of the wall portions preferably being provided

with securing ears 7 and 8 respectively, and a cover 9 is suitably secured removably to the top of the wall and has a filling hole 10 therein preferably provided with a strainer 5 11, the hole being normally closed by means of a cap or plug 12. The two opposite wall portions 3 and 2 are provided on the inner side thereof with journal boxes 13 and 14 respectively, a guide boss 15 being formed 10 on the bottom 1 adjacent to and preferably connected with the box 14, and the outer end of the box 14 is provided with a packing box 16. The boss 15 has a vertically arranged socket-like guideway 17 therein. 15 Three pump castings 18, 18', 18'', are provided, each being alike and adapted to form two pump barrels and necessary ports connected with the barrels. Two of the castings are secured to the inner side of the 20 wall portion 4 by means of cap screws 19 and 19' respectively, the remaining casting being secured to the inner side of the wall portion 5 by means of a cap screw 19'', there being space remaining for another 25 pump if desired. The two pump barrels in each casting are arranged for convenience one above the other, the lower barrel 20 or 20' being a primary pump barrel, the upper barrel 21, 21', or 21'' being a delivery pump barrel. Preferably the lower barrel is provided with a wearing lining 22, and the upper barrel with a lining 23 which obviously may be removed and replaced by new linings. Each primary 30 pump barrel is provided with an inlet port 24 from which a port 25 extends through the lining or bushing of the barrel so as to be approximately mid-way between the ends thereof. Each casting has a socket 35 26 in the upper portion thereof from which an inlet port 27 extends to the lining 23, the latter having a continuing port opening 28 in the wall thereof at a suitable distance from the inner end of the lining. Preferably the delivery pump barrel is longer than the primary barrel, a plunger 29 being closely fitted to move in the lining of the primary barrel, a relatively longer plunger 30 being similarly fitted into the lining of 40 the delivery barrel. The plungers may be variously operated, and it will be understood that when drawn outward the oil enters the barrels through the ports, the latter being closed by the plungers when 45 moved inward, so that the plungers with the ports serve as check valves to cut off the supply of oil to the cylinders. Each casting has a lateral projection 31 in which is an outlet port 32 extending from the inward 50 end of the primary pump barrel, the casting having also an outlet port 33 extending from the inner end of the delivery pump barrel. Three discharge pipes 34, 34', and 34'' are provided for the respective pumps, 55 each pipe being screwed into the upper por- tion of the barrel casting so as to be in communication with the port 33. The lower portion of each pipe is adapted to constitute a valve chest, being provided with a smooth bore 35 that is larger in 70 diameter than the remaining portion of the pipe interiorly so that a shoulder or spring seat 36 is formed at the inner end of the bore. An improved check valve is provided 75 which comprises a plug 37 that is screwed into the lower end portion of the bore 35 and has a conical valve seat 38 on its inner or upper portion, the plug having a port 39 extending therethrough. The lower end of the plug has a slot 40 therein to receive 80 a screw-driver. A valve body 41 is slid- 85 ingly guided in the bore 35 and has a conical lower end 42 in which is a recess 43 adapted to receive the end portion of the valve seat 38. The valve body has longitudinal grooves 44 in its surface for the passage of oil, and a spring 45 is arranged in the bore 35 and seated on the valve body and also against the shoulder 36, an outlet channel 46 extending from the bore through 90 which to discharge the oil into a line pipe which may be suitably connected to the discharge pipe for conveying the oil to such point as may be desired. The improved 95 check valve and its seat are designed to prevent trouble and leakage arising from sedimentary or foreign substances in the oil and permitting the valve to be readily cleaned if necessary. 100 In order to conduct the oil from the primary to the delivery pump barrels a suitable number of connections are provided, there being three pipes 47, 47', and 47'', each pipe being screwed into the top of the projection 31 of a barrel casting so as to 105 have communication with the port 32, and the lower portion of the pipe is adapted to constitute a valve chest having a check valve substantially as above described, the pipe having a bore 35' at the end of which 110 is a shoulder 36', a plug 37' being screwed into the mouth of the bore and having a conical valve seat 38' thereon, a port 39' extending through the plug, the plug having a slot 40' in its lower end. A valve body 41' is arranged in the bore and has a conical end 42' normally arranged on the valve seat, the end of the body having a recess 43' therein to receive the end portion 115 of the seat, and the exterior of the valve body has grooves 44' to form passages for the oil. A spring 45' normally holds the valve yielding to its seat. The pipe has a channel 48 therein extending from the bore 35' to the upper end of the pipe, the upper end having a journal portion 49 that has a relatively smaller external diameter than the remaining portion, and the channel 120 is closed by means of a cap 50 screwed onto the journal portion, the wall of the latter 125 130

having a port 51 extending to the bottom of an external groove 52 for the passage of oil outward and about the journal irrespective of the position in which the pipe 47 5 may be after screwing it into the projection 31. A collar 53 is fitted closely onto the journal portion 49 so as to cover the groove 52 and it has a horizontal branch pipe 54 thereon in which is a channel 55, 10 the under portion of the branch pipe having a socket 56 from which a duct 57 extends to the channel 55. Each branch pipe has a valve body 58, 58', or 58'' thereon that has a chamber 59 therein communicating 15 with the channel 55, there being a valve seat 60 in the bottom of the chamber, the bottom having a drop nozzle 61 thereon. A valve stem 62, 62', or 62'' is suitably screwed into the valve body and has a valve 20 63 on its inner end adapted to regulate the feeding of the oil past the valve seat. A vertical branch pipe 64, 64', or 64'' is screwed into each socket 26 for conducting the oil to the delivery pump barrel, and a 25 sight feed glass 65, 65', or 65'' is connected to the valve body 58 and also the branch pipe 64.

In order to permit the pump to run steadily and not create over-pressure, each 30 branch pipe 54 preferably is provided with an over-flow pipe 66 that is connected to the socket 56, there being a channel 67 in the pipe to receive the surplus oil from the port 57, the lower portion of the pipe being 35 adapted to constitute a valve chest having a smooth bore 68 therein at the inner end of which a valve seat 69 is formed, the wall of the valve chest having an outlet port 70 therein that is normally closed by a valve 71 40 held on the valve seat by means of a spring 72 that is supported on a plug 73 screwed into the lower end of the pipe and having a drain duct 74 therein. It will be understood that resistance of the spring may be 45 varied so that more or less pressure for feeding the oil may be obtained before overflow occurs.

The means preferably employed for actuating the pump plungers preferably comprises a drive-shaft 75 that is rotatably mounted in the boxes 13 and 14 and extends through the packing box 16, a cylinder being rotatably mounted eccentrically on the shaft so as to constitute a relatively long eccentric 50 55 60 65 70 75 80 85 90 95 100 105 110 115 120 125 130 135 140 145 150 155 160 165 170 175 180 185 in contact with the rack-bar. The outer end of the shaft 75 is provided with a hand crank 108 whereby the shaft may be rotated to operate the pumps temporarily if for any reason it may be so desired or required. The under portion of the casing preferably has a drain hole 109 therein, it being understood that in the type of piston and valve shown the steam may be exhausted through the piston rod and into the casing, so that the latter serves as a muffler besides covering and protecting the gearing.

In practical use the reservoir is placed most advantageously in a protected and warm position rather than in an exposed situation remote from the engineer or attendant and therefore may be readily observed and inspected, the reservoir being periodically supplied with lubricating oil as may be required. In operation, the driving shaft 75 is rotated and reversed alternately and therefore the dog 82 causes intermittent rotation of the ratchet wheel 77 and the eccentric 76 on the shaft, the eccentric imparting reciprocating motion to the pump plungers. The oil is received from the reservoir into the primary pump barrel and forced out through the pipe 47, thence through the branch 54, the oil being fed through the drop nozzle 61 and passing through the pipe 64 and thence to the delivery pump barrel, any surplus returning through the pipe 66 to the reservoir. From the delivery pump barrel the oil is forced through the discharge pipe connected therewith. The speed of the motor may be regulated by means of the throttle-valve 101 according to the requirements, the supply of oil being regulated by means of the valve 63 as will be understood, and it will be clear that the lubricant-feeder may be operated before the machinery has started so that the machinery is immediately lubricated upon being put in motion, and in many cases the feeder may be stopped some time before the machinery is stopped so that the waste of lubricant is avoided. In some cases it may be convenient to operate the feeder by means of the hand crank in order to fill the pipe lines and supply the lubricant in case compressed air is employed for actuating the motor, and when the supply of compressed air may not be available until after a compressor is in operation.

It will be understood that various modifications in the details of construction may be made within the scope of the appended claims, and that various results of the operation of the oil feeder will be clearly understood from the detail description of the construction and function of the various parts thereof.

Having thus described the invention, what is claimed as new is—

1. In a lubricant-feeder, the combination

of a reservoir, a casing secured to the exterior of the reservoir and provided with a journal bearing, a shaft rotatably mounted in the wall of the reservoir and extending through said journal bearing, a feed-pump supported in the reservoir and operatively connected with the shaft, a pinion in said casing and secured to said shaft, a motor having a piston rod that extends into said casing, a rack-bar connected to said rod and having engagement with said pinion, a guide for said rack-bar supported in said casing, and a hand crank connected to said shaft on the outer side of said casing.

2. In a lubricant-feeder, the combination of a pump barrel having an inlet port in its side and an outlet port in its inner end, a pipe removably connected at one end with the outlet port and having a relatively large bore extending from the connected end, a plug screwed into said end and having a conical valve seat on its inner end, the plug having a port extending from the outlet port through said seat, a valve body movably fitted into said bore and having a conical end in which is a recess normally receiving the end portion of said seat, said body having longitudinal grooves in its outer side, a spring interposed between said valve body and the bottom of said bore, and a plunger movable in the barrel.

3. In a lubricant-feeder, the combination of a reservoir comprising two opposite side wall portions, a power cylinder having a supporting plate fixed on one end portion thereof that is fixedly secured to the exterior of one of the wall portions, the plate supporting the cylinder in projected position, a feed-pump supported in the reservoir, a shaft rotatably mounted in the two wall portions and extending through said one of the portions, a toothed pinion exterior to the wall portion and secured to the shaft, said shaft being adapted to actuate the feed-pump, a piston movable in the cylinder, a rod connected to the piston and extending adjacent to said one of the wall portions, a toothed rack-bar connected to the rod and having engagement with the pinion, and a guide supported by said wall portion for guiding the rack-bar.

4. In a lubricant-feeder, the combination of a reservoir comprising a bottom and a wall on the bottom comprising four portions, two journal boxes fixed on the inner sides of two opposite portions respectively of the wall, a boss fixed on the bottom of the reservoir adjacent to one of said boxes and having a vertical guideway therein, a shaft rotatably mounted in said boxes, an eccentric rotatable on said shaft, a ratchet wheel rotatable on said shaft above said boss and secured to said eccentric, a spring seated in said guideway, a pawl movably guided in said guideway upon said spring and en-

gaging said ratchet wheel, an arm fixedly secured to said shaft between said wheel and said one of the boxes, a dog carried by said arm and engaging said ratchet wheel, a
5 pump barrel supported in said reservoir, a plunger in said barrel, and a yoke secured to said plunger and embracing said eccentric.

In testimony whereof, I affix my signature in presence of two witnesses.

JOHN RICE.
